UNITED STATES PATENT OFFICE.

EMIL SCHIMANEK, OF BUDAPEST, HUNGARY, ASSIGNOR TO THE FIRM HERMES MAGYAR ALTALÓNOS VÁLTÓÜZLET RÉSZVÉNYTÁRSASÁG, OF BUDAPEST, HUNGARY.

CARBURETOR.

Application filed February 26, 1926, Serial No. 90,893, and in Hungary June 27, 1925.

This invention relates to a carburetor for automatically regulating the ratio of air and fuel according to the different speeds of the internal combustion engine with which it is employed. In this carburetor a regulating piston is provided to alter the section of passage of the air flowing through the carburetor and, simultaneously, the section of passage of the fuel admission, in such a manner that the ratio of mixture is either kept constant by the changes of position of said piston or is altered according to a predetermined scheme. It will be understood that for each speed of the engine there is a corresponding position of said piston, determining the ratio of mixture of air and fuel.

The object of this invention is to allow the ratio of air and fuel in the mixture to be altered either automatically or at will by the operator, even if the speed of the engine is not changed.

According to the invention, the regulating piston is adapted to control the area of the air passage into which the fuel channel discharges, on the one hand by its vertical movement caused by changes in the speed of the engine and on the other hand by the rotation of said piston which may be effected either by the operator or by changes in atmospheric pressure.

The annexed drawing shows two embodiments of the invention.

Figure 1 is a sectional view of a carburetor in which the adjustment of the piston is effected manually;

Fig. 2 is a vertical section of the piston on line 2—2 of Fig. 1;

Fig. 3 is a sectional view of another form, in which the regulation of the air and fuel takes place automatically according to the changes in atmospheric pressure;

Fig. 4 shows a detail of Fig. 3 on a larger scale.

With reference to Fig. 1, 1 is the casing of the carburetor, 2 is the air inlet, 3 is a float chamber containing liquid fuel 4, and 5 is a float located therein. 6 is a lever pivoted at 7, resting on the top of float 5, and 8 is a valve controlling the admission of liquid fuel from the fuel conduit 9 to the float chamber 3. 10 is the stem of valve 8, resting upon lever 6. 11 is a cylindrical upper part of the casing 1 of the carburetor, and 12 is a piston movable therein, said piston serving as a means for automatically reg-

ulating the area of the passages for air and fuel admission. 14 is a mixing chamber, and 13 is an opening connecting the cylindrical part 11 of the casing 1 with said mixing chamber 14. 15 is a cylindrical projection or skirt on the piston 12 co-operating with said cylindrical part 11 to control the area of opening 13. This latter is shaped to have an oblique edge 16, and projection 15 has an oblique edge 17 parallel with edge 16.

Channel 19 of the hollow stem 18 of piston 12 is connected with horizontal channels 20 (Fig. 2) discharging within the area of opening 13. Channels 21 are provided to connect the discharge ends of the channels 20 with the upper side of piston 12. A sleeve 22 provided with a circular base plate 23 is secured to the lower end of stem 18, and a perforated disc 24 is secured between stem 18 and sleeve 22. Plate 23 fits loosely into the lower cylindrical part 48 of the carburetor casing. Openings 25 in sleeve 22 admit the liquid fuel through the perforation of disc 24 into channel 19. A tapered needle 26 secured to the bottom of the carburetor casing projects through the perforation of disc 24 into channel 19.

Journalled in stuffing box 27 on the top of the carburetor casing is a shaft 28 provided at its lower end with a disc 29, and piston 12 is provided with an upwardly projecting pin 30 engaging an opening 31 in disc 29. 32 is a controlling lever secured to the upper end of shaft 28.

The operation of the carburetor is as follows:

The fuel is admitted from the fuel conduit 9 through valve 8 into the float chamber 3 until float 5 closes valve 8 by means of lever 6. The air is sucked in through opening 2 into the carburetor casing and passes through opening 13 into the mixing chamber 14. At the same time the fuel passes through openings 25 and the perforation of disc 24 into the channel 19 of stem 18 of piston 12 and, owing to the suction, rises in channel 19 in order to discharge through channels 20 and opening 13 into the mixing chamber. The mixture leaves the carburetor through the induction pipe or conduit 49. As the chamber 33 above piston 12 communicates through channels 21 with the discharge end of the fuel passage 19—20, the pressure above piston 12 will be the same as that which causes the suction of fuel. The pres-

sure acting on the lower face of piston 12 will be that of the atmosphere. The position of equilibrium of piston 12 will be determined by the speed of the engine.

5 It will be understood that the pressures acting at both sides of the piston should be static ones. The connection of the discharge end of the fuel channels 20 by means of channels 21 with the closed chamber 33 above 10 piston 12, in which the air is at rest, causes the dynamic pressure occurring at the discharge end of the fuel channel to act as a static pressure upon the piston. In order that the pressure below the piston may be 15 substantially a static one, the area of the piston must be a multiple of the free area of the air admission opening 13, so that the velocity of the air under the piston will practically not alter the pressure. The pressure 20 acting on the upper side of the piston will be less than the pressure acting on the lower side so that the piston would be lifted to its uppermost position if its weight did not counteract the lifting action. As 25 this weight is constant, the piston will reach a state of equilibrium if the difference between the pressures acting on the lower and upper sides of said piston is constant. As, however, owing to the great area of the piston, the pressure below the piston is independent 30 of the quantity of the air flowing through the carburetor, the pressure acting upon the upper side of the piston must be regulated automatically to a constant value 35 independently of the quantity of air flowing through the carburetor. Hence the velocity of the air at the spot where the mixing of the air and fuel takes place will be regulated to a value which is constant independently 40 of the quantity of air sucked in by the engine; that is to say, the piston will assume a position in which the area of opening 13 is altered in such a manner that the velocity of the air in said opening will be 45 constant at any speed of the engine. With alterations of the position of the piston 12, however, the position of disc 24 with respect to needle 26 and, correspondingly, the section 50 of passage of the perforation of said disc left free by needle 26 are altered, so that the ratio of fuel and air admitted through disc 24 and opening 13 will be altered in conformity with the shape of needle 26, either according to a predetermined 55 scheme or kept constant throughout the range of speed of the engine. Generally, it will be endeavoured to keep the ratio of air and fuel constant throughout the range of speed of the engine. This ratio will be 60 termed the "fundamental ratio".

It is, however, desirable to alter this fundamental ratio according to the nature of the fuel used, or according to the specific weight of the air, which varies within wide 65 limits if the motor is used on air craft. For

this purpose means are provided according to my invention allowing alteration of the ratio of the sections of passage of the air and fuel in the carburetor in any position of the automatic piston 12 without altering 70 the position of this latter.

According to Fig. 1, this is effected by turning handle 32, so that shaft 28 turns piston 12 by the intermediary of disc 29 and pin 30, and thereby produces a decrease 75 or increase of the distance of edge 17 of skirt 15 from edge 16 of opening 13 without altering the level of piston 12. This adjustment by twisting piston 12 does not affect the automatic adjustment of said piston 80 in the vertical direction. Plate 23 serves to choke the vibrations of piston 12.

According to Figs. 3 and 4, the adjustment of the piston is effected automatically 85 by changes in atmospheric pressure.

For this purpose the adjusting disc 29 that engages pin 30 of piston 12 is journalled on a stud 41, secured to a diaphragm 42 which hermetically closes a chamber 43. The chamber 43 is filled with a gas under a certain pressure, for example the normal atmospheric pressure at sea level. If the atmospheric pressure decreases, the gas filling chamber 43 expands and lowers stud 41 with disc 29. An oblique slot 44 (Fig. 4) formed 90 in a projection 45 on disc 29 engages a pin 46 secured in the carburetor casing, so that the vertical displacement of disc 29 causes, by the co-operation of slot 44 and pin 46, the rotation of said disc and, by the mediation 95 of pin 30, the rotation of piston 12.

I claim as my invention:

1. A carburetor, comprising a casing partitioned internally to form an air inlet chamber and a mixing chamber, such partition having an opening providing communication between said air and mixing chambers; a fuel chamber in said casing; a fuel conduit leading from the fuel chamber to the mixing chamber to discharge the fuel 105 thereinto; a piston movable vertically within the air chamber to control the effective area of said opening; a depending skirt on the piston; a suction chamber in said casing at the opposite side of the piston from said air chamber and communicating with the same, said suction chamber transmitting the engine suction to said piston to effect its vertical movements; and means for rotating the piston to cause its skirt to vary the said 110 effective area of said opening independently of the vertical position of said piston.

2. A carburetor, comprising a casing; a cylindrical partition in the casing to form an air inlet chamber and a mixing chamber, such partition having an opening providing communication between said air and mixing chambers; a fuel chamber in the bottom of the casing; a piston movable vertically within said partition to control the effective 115

- area of said opening and having a hollow stem submerged at its inlet end in the fuel in the fuel chamber and discharging the fuel at its outlet end through said opening into 5 the mixing chamber; a depending skirt on the piston; a suction chamber in the casing above the piston for transmitting the engine suction to said piston to effect its vertical movements, said suction chamber communicating with the air chamber; and means for 10 rotating the piston to cause its skirt to vary the said effective area of said opening independently of the vertical position of said piston.
- 15 3. A carburetor, comprising a casing; a cylindrical partition in the casing to form an air inlet chamber and a mixing chamber, such partition having an opening providing communication between said air and mixing 20 chambers; a fuel chamber in the bottom of the casing; a piston movable vertically within said partition to control the effective area of said opening and having a hollow stem which is submerged at its lower or 25 inlet end in the fuel in the fuel chamber, the upper end of the bore of said stem having one or more outlet channels leading from it to discharge the fuel through said opening into the mixing chamber; a depending 30 skirt on the piston; a suction chamber in the casing above said piston for transmitting the engine suction to the latter to effect its vertical movements, said suction chamber communicating with said outlet 35 channels by means of separate channels formed through the piston; and means for rotating said piston to cause its skirt to vary the said effective area of said opening independently of the vertical position of the piston.
4. A carburetor, comprising a casing provided with a mixing chamber having a single opening for admitting both air and fuel thereto for admixture, means for supplying air and fuel separately to said opening, a suction-operated piston movable vertically in the casing to vary the effective area of said opening and thereby control both the air supply and the fuel supply to said mixing chamber, a depending skirt on the piston, and means for rotating said piston to cause its skirt to vary the effective area of the opening and thereby control the air and fuel supply independently of the vertical position of the piston.
5. A carburetor, comprising a casing provided with a mixing chamber having a single opening for admitting both air and fuel thereto for admixture, means for supplying air and fuel separately to said opening, a suction-operated piston movable vertically in the casing to vary the effective area of said opening and thereby control both the air supply and the fuel supply to said mixing chamber, a depending skirt on the piston, a vertical guide member on said piston, and means engaged with said guide member to rotate the piston and thereby cause its skirt to vary the effective area of the opening and, consequently, the air and fuel supply independently of the vertical position of the piston.

In testimony whereof I affix my signature.
